UNITED STATES PATENT OFFICE.

MARION JAY HARDEN, OF AKRON, OHIO.

COMBINATION TABLE AND SEAT.

1,193,544.

Specification of Letters Patent.

Patented Aug. 8, 1916.

Application filed November 10, 1915. Serial No. 60,766.

To all whom it may concern:

Be it known that I, MARION JAY HARDEN, a citizen of the United States, residing at Akron, in the county of Summit and State of Ohio, have invented a new and useful Combination Table and Seat, of which the following is a specification.

The device forming the subject matter of this application is a convertible article of furniture adapted to be employed as a table, as a seat without a back, or as a seat comprising a back.

The invention aims primarily, to provide novel means for assembling the top of the structure with the legs or posts thereof, thereby to convert the table into a seat.

Another object of the invention is to provide novel means for holding the table top in place.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawing:—Figure 1 is a front elevation; Fig. 2 is a longitudinal section; Fig. 3 is a cross section taken on the line 3—3 of Fig. 1, the line 2—2 in Fig. 3 designating the cutting plane on which Fig. 2 is taken; Fig. 4 is a fragmental perspective showing the manner in which the top is interlocked with the posts when it is desired to convert the top into a seat back; Fig. 5 is a fragmental horizontal section taken through one of the cleats on the top.

In carrying out the present invention there is provided a frame comprising front posts 1, rear posts 2, a seat 3 connecting the posts 1 and 2, and extended forwardly and rearwardly beyond the outer faces of the posts 1 and 2 to form ledges 4, end walls 5 uniting the posts 1 and 2 and extended upwardly above the seat 3, arm rests 6 extended beyond the posts 1 and 2 and supported on the end walls 5, a front strip 8 connecting the posts 1 below the seat 3, and

a rear strip 9 connecting the posts 2 below the seat 3. The end walls 5 may be provided with magazine racks 7.

Supported by the posts 1 and 2 is a top 22 provided with depending cleats 23 engaging the outer faces of the posts. Any suitable means may be provided for maintaining the top 22 properly positioned with respect to the posts 1 and 2. In the present instance, recesses 26 are formed through the cleats 23, near to their ends, and in the recesses are mounted to reciprocate plungers 27, having enlarged ends 28 defining shoulders 29. Surrounding the plungers 27 are compression springs 34, abutting at one end against the shoulder 29 and abutting at the other end against a plate 30 secured to the outer face of the cleat 23. The plate 30 carries an outstanding cam 31 and on the end of the plunger 27 there is a knob 32 provided with a cam face 33 adapted to coact with the cam 31.

In practical operation, the ends 28 of the plungers 27 coact with the inner edges of the posts 1 and 2, as shown best in Fig. 3, thus to hold the top 22 in place.

Fixed to and depending from the top 22 are angular keepers 25. In the inner edges of the posts 1 and 2, at the tops of the posts, seats 24 are fashioned, the same being adapted to receive the keepers 25 under circumstances which will be pointed out hereinafter.

In practical operation, presupposing that the parts are arranged as shown in Fig. 3, the ends 28 of the plungers 27 are advanced by the action of the springs 34 and engage the inner edges of the posts 1 and 2, thereby to prevent the top 22 from shucking about. Let it be supposed, however, that it is desired to convert the structure from a table into a seat. Under such circumstances, the table top 22 is lifted off the posts 1 and 2 and is placed in a vertical position as shown in Fig. 4. The lower edge of the top 22 then comes into contact with one of the ledges 4 and thus the top is upheld. The keepers 25 on the top are received in the seats 24 in the posts 1—1 or 2—2 and thus the top is sustained in such a manner that it constitutes a back coöperating with the seat 3. When the angular keepers 25 are engaged in the seats 24 of the posts, and when the top 22 has been converted into a back, the latches 27 may be retracted, so that the ends 28 thereof will not mar the posts 1—1

or 2—2. Under such circumstances, by means of the knobs 32, the plungers 27 are rotated, whereupon the cams 33 and 32 will coact to retract the latches, so that the ends 5 28 of the latches will lie within the contour of the cleats 23.

Having thus described the invention, what is claimed is:—

1. An article of furniture comprising 10 posts; a seat connecting the posts; a top resting on the posts; and angular keepers carried by the under surface of the top, the ends of the keepers projecting outwardly in opposite directions, the posts being provided in their inner edges with longitudinal 15 grooves which open through the upper ends of the posts, the grooves receiving the said ends of the keepers when the top is disposed vertically, thereby to hold the top in coöperating relation with the seat, to serve 20 as a back.

2. In a device of the class described, posts; a seat connecting the posts; a top

supported on the posts; locking devices carried by the top and coacting with the posts 25 to hold the top against movement with respect to the posts; fingers carried by the under surface of the top, there being openings in the posts adjacent their upper ends and adapted to receive the fingers, thereby 30 to hold the top in an upright position and substantially at right angles to the seat, to form a back coöperating with the seat; and means for holding the latches in retracted positions, thereby to prevent the latches 35 from engaging the posts when the top is in back forming relation with respect to the seat.

In testimony that I claim the foregoing as my own, I have hereto affixed my signature in the presence of two witnesses.

MARION JAY HARDEN.
